CLAIM

The ornamental design for a decorative self-watering pot, as shown and described.

DESCRIPTION

FIG. 1 is an exploded perspective view of a decorative self-watering pot showing my new design;

FIG. 2 is a top plant view of the upper part of FIG. 1;

FIG. 3 is a bottom plan view of the upper part of FIG. 1;

FIG. 4 is a side elevational view of the upper part of FIG. 1 it being understood that the opposite side is a mirror image thereof;

FIG. 5 is a top plan view of the lower part of FIG. 1;

FIG. 6 is a bottom plan view of the lower part of FIG. 1;

FIG. 7 is a side elevational view of the lower part of FIG. 1 it being understood that the opposite side is a mirror image thereof;

FIG. 8 is a side elevational view of the upper and lower parts of the decorative self-watering pot in assembled condition it being understood that the opposite side is a mirror image thereof; and,

FIG. 9 is a bottom plan view of FIG. 8.

The broken line showing of environmental structure is for illustrative purposes only and forms no part of the claimed design.
